CLAIM

The ornamental design for a toner cartridge, as shown and described.

DESCRIPTION

FIG. 1 is a front, right top perspective view of a toner cartridge showing a first embodiment of our new design;
FIG. 2 is a front, left, bottom perspective view thereof;
FIG. 3 is a front view thereof;
FIG. 4 is a rear side view thereof;
FIG. 5 is a left side view thereof;
FIG. 6 is a right side view thereof;
FIG. 7 is a top plan view thereof;
FIG. 8 is a bottom plan view thereof;
FIG. 9 is a front, right top perspective view of a toner cartridge showing a second embodiment of our new design;
FIG. 10 is a front, left, bottom perspective view thereof;
FIG. 11 is a front view thereof;
FIG. 12 is a rear side view thereof;
FIG. 13 is a left side view thereof;
FIG. 14 is a right side view thereof;
FIG. 15 is a top plan view thereof; and,
FIG. 16 is a bottom plan view thereof.
The broken lines shown in the drawings illustrate portions of the toner cartridge that form no part of the claimed design.
